(57) **CLAIM**

The ornamental design for a curved keypad, as shown and described.

DESCRIPTION

FIG. 1 is a front perspective view of a curved keypad according to one embodiment of the present invention.

FIG. 2 is a rear perspective view of the curved keypad shown in FIG. 1.

FIG. 3 is a top view thereof.

FIG. 4 is a bottom view thereof.

FIG. 5 is a front view thereof.

FIG. 6 is a rear view thereof.

FIG. 7 is a left view thereof.

FIG. 8 is a right view thereof.

FIG. 9 is a front perspective view of a curved keypad according to another embodiment of the present invention, which is similar to FIG. 1 but with additional features disclaimed in broken lines.

FIG. 10 is a rear perspective view of the curved keypad shown in FIG. 9.

FIG. 11 is a top view thereof.

FIG. 12 is a bottom view thereof.

FIG. 13 is a front view thereof.

FIG. 14 is a rear view thereof.

FIG. 15 is a left view thereof; and,

FIG. 16 is a right view thereof.

Any elements shown in broken dash lines form no part of the claimed design, but are instead included to show environmental aspects thereof. The broken dash-dot lines illustrate boundaries of the claimed design of that embodiment but do not define part of the claimed design themselves.
